Attorney.

UNITED STATES PATENT OFFICE.

EMIL BAUMANN, OF ST. LOUIS, MISSOURI.

RESILIENT TIRE.

1,424,231.

Specification of Letters Patent. Patented Aug. 1, 1922.

Application filed June 7, 1922. Serial No. 568,475.

To all whom it may concern:

Be it known that I, EMIL BAUMANN, a citizen of the United States, residing at St. Louis, in the State of Missouri, have invented certain new and useful Improvements in Resilient Tires, of which the following is a specification containing a full, clear, and exact description, reference being had to the accompanying drawings, forming a part hereof.

My invention consists in the novel construction and arrangement of parts herein-after particularly described and distinctly claimed.

The object of my invention is to provide an improved mechanical spring-filling (or a resilient mechanical insert) for the outer-casings of pneumatic-tires; which shall be simple and durable in construction, as well as of low cost; and which will take the place of the inner-tube of pneumatic-tires; and which shall possess the same resiliency as an inner-tube, but be devoid of the disadvantages thereof, such as the danger of being punctured, mutilated, or requiring frequent repairs that involve much expense and loss of time.

In the drawings,

Fig. 1 is a cross-section of the present form of my invention, applied to the usual demountable-rim, and outer-casing, of an automobile wheel; the section being taken on the line 1—1 of Fig. 2, but showing the parts greatly enlarged, for the sake of clearness.

Fig. 2 is a detail side-elevation, partly in section, of a portion of an automobile-wheel and its tire-casing, having my invention applied thereto.

Fig. 3 is a detail fragmentary inverted view of one of my pistons or plungers; showing the means for locking same against turning, and

Fig. 4 is a detail side-elevation, partly in section, of one of my tread-members and its attached piston or plunger, as it appears before assembling same with other cooperating parts.

The numeral 1 designates the usual wooden felly, 2 the spokes, and 3 the hub, of an ordinary automobile-wheel, whether the same is of the form herein shown, or of other construction, with either wood or metal spokes, or (if desired) the said felly may be of metal.

In the present case, I have illustrated a metallic-rim 4 on the outer periphery of the

said wooden felly 1, and demountable clincher-rings 5 are held in place by the usual bolts 6, for the purpose of holding the tire-casing 7 in position; but my invention 60 may be used with other forms of rims, such as the ordinary clincher-rim having integral clincher-flanges, and the construction and operation of my invention will be substantially the same in either case. 65

The present form of the mechanical substitute for inner-tubes.

In the present form of my substitute for inner-tubes, I provide a base-ring 8, of any 70 suitable material (preferably of metal), and having such size that it may be detachably mounted on the periphery of the said wheel-rim 4, or upon the outer surface of the felly 1, in case the latter is of metal. 75

Said base-ring 8 is rectangular in cross-section, and is of about half the width of the said felly 1, so there will be ample space on each side of it, for the beaded or clincher portions of the casing 7. 80

A plurality or multiplicity of pistons or plungers 9, (preferably at least twice as many of them as there are wheel-spokes 2), are mounted to slide radially in bearing-nuts 10, which are provided with screw-threads 85 upon their outer surfaces, and are screwed into radial internally-threaded holes or seats 11 in said base-ring 8.

Each of said pistons or plungers 9 has, preferably, an enlargement 12 at its outer 90 end, with which is cast integral or fixed thereon a tread-member or tread-engaging section 14, which is curved in cross-section, as shown in Fig. 1, to snugly fit the interior of the tire-casing 7. 95

The construction and arrangement of the said tread-members 14 is such that they overlap the adjacent tread-members and form a continuous support for the tire-casing, throughout the internal circumference of 100 said casing; the under-lapped portions of said tread-members being formed with a recess or depression 15, to receive therein the over-lapped portions; thus obviating any elevation of the overlapped ends beyond the 105 outer periphery of said members, and consequent sharp-edged projections, which would wear away or cut the fabric of said tire-casing, and providing a comparatively smooth

and regular supporting-surface for said casing, throughout the inner circumference of 110 the latter.

Furthermore, such overlapped and recessed construction of the said tread-members 14 forms closed joints between the members, and yet provides for their ready application and removal, as well as permitting relative yielding movement circumferentially of the wheel to the required extent, to compensate for the contraction and expansion of the tire-casing during use.

10 As previously stated, the said tread-members 14 are preferably cast integral with their respective plungers or radially-mounted supporting-rods or posts 9; the point at which said members join their said plungers 9 being preferably at a point near the free end of the said recessed portion of each member; so that said recessed (or depressed) portion of each member will rest against and be firmly supported by the plunger to which it 15 is attached, while the opposite (or unrecessed) end of each tread-member will overlap the next adjacent recessed portion of another tread-member, and rest in contact therewith, and will be firmly supported by 20 its post or plunger 9. Fig. 2.

In other words, the said overlapped tread-members are of sufficient length to reach from one of said posts or plungers 9 to the next adjacent plunger, and overlap the same, 30 as well as overlap the adjacent tread-member on one side, and underlap the next adjacent tread-member on the opposite side.

Such construction is very efficient and durable, for the reason that each tread-member is thus provided with two posts or plungers 9, which transmit the load or weight 35 equally to both ends of the tread-members, and make the structure very much stronger and more durable than if but a single post 40 for each tread-member were provided.

Said plungers or posts 9 are limited in their outward movement by pins or lugs 16, which project laterally from the inner ends of said plungers, and contact with the adjacent inner end of said bearing-nuts 10, in 45 which are preferably formed, Fig. 3, radial grooves 17 in which said pins or lugs rest, and act as locks for said nuts, to prevent same from turning upon their plungers, except when it is desired to tighten or loosen 50 the plunger-springs, which will now be described.

A plunger-spring 18 is provided for each of said plungers 9, to normally hold the 55 latter (as well as said tread-members 14) at the limit of their outward movement, which is that in which they are shown in Figs. 1 and 2.

In the present form of my invention, said 60 springs 18 are of the form known as coil-springs, and one of them is mounted upon each of said plungers 9, with their outer ends resting in contact with the inner surface of the adjacent tread-member 14, while 65 their inner ends engage spring-seats on the

outer ends of said bearing-nuts 10. Said spring-seats may, of course, be of any approved form, but in the present case they have a spring-retaining sleeve 19 projecting outwardly from the inner end of said nuts 70 10, and extending into said spring a short distance, to hold said spring in proper position.

The outer ends of said springs 18 engage 75 said enlargements 12 of the outer ends of said plungers or posts 9, and are thus held in proper position.

A grease-cup or lubricant-receptacle 20 is formed in (or placed in) the said metallic- 80 rim 4 and in said felly 1, at a point directly opposite the inner end of each of said pistons or plungers 9, so that each time the latter are forced inwardly (while the tire is traveling along a road or pavement) the inner ends of said plungers will dip into the 85 grease or lubricant that is in said grease-cups, and then be drawn out with a supply of grease, which will be distributed to the plunger-bore of said bearing-nuts 10, and will also find its way to the said springs 18 90 and all the other internal parts of the device, and keep same properly greased or oiled, and thus also protect from rust and corrosion all of said parts, as well as keep them properly lubricated during use of the 95 tire.

It will be understood, that at every revolution of the wheel carrying the tire, the said springs 18 will be compressed and released alternately, and the said plungers 9 100 will be forced into and withdrawn from the said grease-cups 20 a certain distance, more or less, depending upon the weight of the load carried by the tire, at every revolution of the latter.

To prevent the said base-ring 8 from crawling (either forward or backward) upon the said rim 4 and felly 1, a transverse key-seat 21 is cut in the inner wall 110 of said base-ring, and a key or projection 22 is fixed upon the outer periphery of the said metallic-rim 4, and extends into said key-seat, and prevents circumferential movement of said base-ring upon the rim and felly of the wheel.

However, said key 22 will not prevent lateral movement of said base-ring 8, and will therefore not interfere with the ready placing and removal of the base-ring and parts carried thereby.

The operation.

The operation of my invention is very simple, and will be readily understood by an inspection of Figs. 1 and 2, in which the 125 various parts are shown in their normal operative positions.

It will be seen that when the wheel carrying the tire moves along the road, the said outer-casing 7 will be compressed where 130

same is in contact with the road or pavement, and the corresponding tread-members 14 will be forced inwardly against the power of their springs 18, and said plungers 9 will 5 slide in their bearings in said bearing-nuts 10, until the inner ends of said plungers dip into the grease or lubricant contained in said grease-cups 20, and the parts will be thereby thoroughly lubricated, as before 10 described.

As many as two, and sometimes three or 15 four of said tread-sections 14 and their springs 18, will (at one time) be forced inwardly by the weight of the load carried by the tire.

Of course, the lighter the load the smaller 20 the number of tread-members or sections 14 forced inwardly at one time, vice versa.

The overlapped construction of the said 25 tread-members 14, previously described, causes a number of adjacent tread-members to move inwardly against the power of their springs, in unison, so that each of such inwardly-moved tread-members and their 30 springs act in combination, and thus are enabled to support very heavy loads without breaking or damage to any of the parts 35 of my invention.

I do not limit myself to the exact form 40 and arrangement of parts shown in the drawing, as it will be readily understood that changes and improvements may be made by skilled workmen, without departing from the spirit of my invention, and 45 still be within the scope of my claims.

The casing 7, containing my self-contained 50 inner-tube mechanical substitute, may be readily removed from the wheel, for repairs or inspection, by merely removing the nuts 40 from the bolts 6 of the clincher-rings 5, then detaching the one of the latter which is on the outside of the wheel; and then 55 sliding said casing and its contents laterally off of the wheel rim 4.

Mounting the casing 7 and its contained 60 inner-tube mechanical substitute, may also be easily accomplished, by reversing the de-mounting operation, just described, and placing all of the parts in the position in 65 which they are shown in Figs. 1 and 2, much in the same well-known way in which a common partially-inflated inner-tube is first inserted in the casing, and then the latter is placed in position and secured upon the 70 wheel-rim.

Of course, the mounting operation will 75 be more easily accomplished if but little strain is thrown upon the casing by the springs 18 of the invention, and such strain can be easily regulated while the casing and 80 its contents are off the rim, by screwing said bearing-nuts 10 out or in, as required to throw more or less strain on the side-walls of said casing.

If said bearing-nuts 10 are moved out- 85

wardly, there will be more strain thrown on said casing walls; but if said nuts are moved inwardly a slighter strain or "filling" force will be exerted on said casing.

In assembling the plungers 9, bearing-nuts 10, tread-members 14, and base-ring 8, in the casing (which of course should be done before the device is mounted on the wheel-rim), the said casing is preferably laid flat upon a work-bench, table, or the 90 floor, and then the various parts are inserted in the casing, and the tension upon the springs 18 is adjusted, as required, by screwing said bearing-nuts 10 inwardly or outwardly in their threaded seats 11 in said 95 base-ring, after which the casing and the mechanical substitute for an inner-tube contained therein, are ready to be mounted upon the wheel-rim 4, which may be accomplished in the manner previously described.

A suitable forked screw-driver, or spanner, is to be used in tightening up or loosening said bearing-nuts 10, such tool being engaged in the said grooves 17 in the inner 90 ends of said nuts.

In order to turn said bearing-nuts by means of the tool just mentioned, it will be necessary to first disengage said pin 16 from said locking-grooves 17, which may be done 95 by compressing said springs 18, and sliding said plungers 9 inwardly until said pin is removed from the groove which it previously occupied, when said nuts may be turned, as described, and then relocked by 100 allowing said pin to again occupy the proper locking-groove.

The casing 7 protects all of the parts from 105 rain, mud, sand, snow, and moisture, and thereby enables their condition to be continually first-class.

I claim:—

1. A mechanical substitute for the inner-tubes of pneumatic-tires, consisting of a base-ring adapted to be placed within the 110 tire-casing before the latter is mounted on the wheel-rim; a series of sliding plungers projecting radially from said base-ring; overlapping tread-sections mounted on the outer ends of said plungers, so that each of 115 said tread-sections is supported by two adjacent ones of said plungers; and means for yieldingly urging said plungers outwardly, to force said tread-sections into contact with the inner surface of said tire casing. 120

2. A mechanical substitute for the inner-tubes of pneumatic-tires, consisting of a base-ring adapted to be placed within the 125 tire-casing before the latter is mounted on the wheel-rim; a series of bearing-nuts, having radial bearings, and threaded into radial nut-openings in said base-ring; a series of plungers mounted to slide in said radial bearings, and project outwardly beyond the 130

outer periphery of said base-ring; means carried by the outer ends of said plungers, for engaging the inner wall of the tire-casing, and supporting the latter; springs resting at their inner ends upon said bearing-nuts, and having their outer ends in engagement with said means for engaging the inner wall of the tire-casing; and means for preventing creeping of said base-ring upon the wheel-rim; whereby all of the parts above mentioned, may be bodily mounted upon and detached from the wheel-rim, by a lateral movement upon the latter.

3. The combination with the elements recited in the above claim 2, of grease-cups 15 into which the inner ends of said plungers pass, and are withdrawn intermittently by said springs when the device is in use.

In testimony whereof, I have signed my name to this specification in presence of two 20 subscribing witnesses.

EMIL BAUMANN.
